US0D1083020S

(12) **United States Design Patent** (10) **Patent No.:** **US D1,083,020 S**
(45) **Date of Patent:** **** Jul. 8, 2025**

(54) **FURROWED O-RING**

(71) Applicant: **Field Systems Research, LLC**, Lake Oswego, OR (US)

(72) Inventor: **John E. Van Leeuwen**, Lake Oswego, OR (US)

(73) Assignee: **FIELD SYSTEMS RESEARCH, LLC**, Lake Oswego, OR (US)

(**) Term: **15 Years**

(21) Appl. No.: **29/986,450**

(22) Filed: **Jan. 17, 2025**

Related U.S. Application Data

(63) Continuation of application No. 18/951,639, filed on Nov. 18, 2024, which is a continuation of application No. 18/893,948, filed on Sep. 23, 2024, now abandoned.

(57) **CLAIM**

The ornamental design for a furrowed O-ring as shown and described.

DESCRIPTION

FIG. 1 is a top isometric view of a furrowed O-ring of my new design;

FIG. 2 is a top plan view thereof;

FIG. 3 is a top isometric view of the furrowed O-ring with optional additional furrows of my new design; and,

FIG. 4 is a top plan view thereof.

The broken lines in the drawings depict portions of the furrowed O-ring that form no part of the claimed design. Views of the furrowed O-ring that are not shown in the drawings or described herein form no part of the claimed design.

1 Claim, 2 Drawing Sheets
